[57] CLAIM

The ornamental design for a camping trailer, substantially as shown and described.

DESCRIPTION

FIG. 1 is a top perspective view of a camping trailer showing my new design.

FIG. 2 is a top plan view thereof.

FIG. 3 is a front elevational view thereof.

FIG. 4 is a left side elevational view thereof.

FIG. 5 is a right side elevational view thereof.

FIG. 6 is a rear elevational view thereof.

FIG. 7 is a rear elevational view thereof with the top portion in raised condition.

FIG. 8 is a right side elevational view of FIG. 7.

The broken lines in the drawing are for illustrative purposes only.
